WINDOW LOCK

Frank C. Gorham, Los Angeles, Calif.

Application January 30, 1945, Serial No. 575,209

5 Claims. (Cl. 292—342)

1

This invention relates to window locks of the type for limiting the opening movement of the lower or the upper window sash, or both, to a predetermined distance relative to each other.

The primary object of the invention is to provide an improved window lock of this type which is simple and inexpensive, yet highly effective in performing its intended function, and which is quickly and easily installed.

A further object of the invention is to provide a window lock comprising two members, one of which is adapted to be fixed to the upper sash, but does not interfere with the movement of either sash relative to the other, and the other of which is detachably supported from the first member and extends into the path of movement of the lower sash to limit the movement thereof, said detachable member being removable by merely rotating it through approximately 90° and withdrawing it from the fixed member.

Other objects and advantages of the present invention will become apparent to those skilled in the art after consideration of the following detailed description of the preferred embodiment thereof, reference being had to the drawings, in which:

Fig. 1 is an elevational view of a window having upper and lower sliding sashes, with a lock constructed according to the principles of the present invention mounted on the upper sash;

Fig. 2 is an enlarged sectional view taken along the lines 2—2 in Fig. 1;

Fig. 3 is an elevational view of the lock, the dotted line position indicating the manner in which the wedge member is turned for the purpose of removing it from its supporting member;

Fig. 4 is a sectional view taken along the line 4—4 in Fig. 3;

Fig. 5 is a side elevation of another embodiment of the lock; and

Fig. 6 is a sectional view taken along the line 6—6 in Fig. 5.

In the drawings, the reference numerals 5 and 6 indicate respectively the upper and lower sashes of an ordinary window, said sashes being slidable vertically in the usual guides provided in the sides of the window frame 7. The locking device is indicated in its entirety by the reference numeral 8 and comprises a fixed supporting member 9 and a locking wedge 10 which depends therefrom. The supporting member 9 is preferably in the form of a sheet metal stamping and is generally elliptical in shape, with projections 11 at the top and bottom thereof. The projections 11 are provided at their sides with down-

2

wardly-turned prongs 13 which are pressed into the material of the upper sash 5 to attach the member 9 thereto. As shown in the drawings, the member 9 is attached to the sash 5 at any desired elevation above the top of the lower sash 6 so that when the locking wedge 10 is attached to it, relative movement between the upper and lower sashes is limited to an opening width adequate for satisfactory ventilation while preventing unauthorized entry.

A pair of laterally-spaced, oppositely extending ears 15 are stamped to project outwardly from the face of member 9, and the locking wedge 10 is adapted to depend from said ears in a manner that will now be explained.

The locking wedge 10 is preferably stamped from sheet metal and is in the form of an elongated, downwardly tapering wedge of substantially U-shaped cross-section, having a front 20 wall 20 and triangular side walls 21. At its upper and lower ends, the front wall 20 is extended longitudinally to form tongues 22 and 23. The upper tongue 22 is pierced to provide a longitudinally-extending slot 24 which is of such width as to receive the ears 15 between its sides when the wedge is in vertical position, said ears overlying the outer surface of the tongue to retain the latter in place. When the wedge 10 is turned through approximately 90°, as shown in dotted lines in Fig. 3, the length of the slot 24 is sufficient to clear the ears 15, hence the locking wedge can be removed from the supporting member 9. It will be understood of course that the ears 15 on the fixed member may be vertically spaced apart, and the slot 24 in the tongue 22 of the wedge-shaped member horizontally extended to produce the same result. Accordingly, where the terms "horizontal" and "vertical" appear in the claims with reference to these locking members they are merely used in their relative sense for the sake of convenience.

The operation of the lock when it is assembled on the window sash is believed to be fairly obvious and is well illustrated in Fig. 2. The bottom tongue 23 lies relatively flat against the surface of the upper sash 5 and therefore has ample clearance with respect to the adjacent edge of the lower sash 6 as the latter is moved up. Continued movement of the lower sash, however, causes the latter to engage the angular face of the wedge, and further relative movement is thereby prevented. When it is desired to free the sashes for complete opening, it is necessary only to swing the wedge lock 10 up to the horizontal position shown and withdraw it from supporting member 9.

Another form of the invention is shown in Figs. 5 and 6, and in this case the supporting member is designated by the reference numeral 30 and comprises a flat disc having a nail 31 extending through a hole in the center thereof. The nail 31 is preferably fixed to the disc as by soldering, crimping, or by a tight press fit, and has a transversely elongated head 32 which is spaced out from the surface of the disc to accommodate the thickness of the tongue 22. The nail 31 is driven into the material of the sash 5 until the disc 30 lies flush against its surface.

The member 30 is attached to the sash so that the nail head 32 is disposed with its longitudinal axis horizontal. The elongated slot 24 in the upper tongue of the wedge lock 10 is of the same general shape but slightly larger than nail head 32 so that the wedge lock can be attached to or removed from the supporting member by turning it to a horizontal position. In this way, the slotted tongue 22 can be passed over the elongated nail head 32, and when the wedge lock is then allowed to drop to its normal vertical position, the lateral projection of the nail head will overlie the edges of the slot to retain the member 10 in place. The operation of this embodiment is the same as in the previously described construction.

The many advantageous features of my invention are believed to be self-evident from the preceding description, one of the most important of said features being the simplicity of design making possible the ultimate economy of manufacture.

While I have described a preferred and specific form of my invention with some degree of particularity, it will be understood that various changes in design, structure and arrangement over the showing of the drawings may be made without departing from the spirit of the invention.

I claim:

1. A window sash lock comprising, in combination, a fixed member adapted to be attached to an upper window sash, a wedge shaped member adapted to depend from said fixed member and to extend out into the path of the lower window sash to limit the vertical movement thereof, supporting means projecting outwardly from the face of one of said members and having a greater extent in one direction than transversely to said one direction, and means on the other of said members adapted to pass over and receive said supporting means only when the wedge-shaped member is turned at an angle to its vertical position whereby when said wedge-shaped member is in vertical position it is restrained from horizontal movement and is permitted only limited vertical movement.

2. A window sash lock comprising, in combination, a fixed member adapted to be attached to an upper window sash, a wedge-shaped member adapted to depend from said fixed member and to extend out into the path of the lower window sash to limit the vertical movement thereof, horizontally elongated and vertically narrow supporting means projecting outwardly from the face of said fixed member, and means on said wedge-shaped member including a vertically elongated slot adapted to pass over said supporting means only when the wedge-shaped member is turned to bring said slot to a substantially horizontal position and in alignment with the horizontal elongation of said supporting means in order that said wedge-shaped member is posi-

tively locked against dislocation when in vertical position.

3. A window sash lock comprising, in combination, a fixed member adapted to be attached to an upper window sash, a wedge shaped member adapted to depend from said fixed member and to receive a vertical force from the lower window sash, and attaching means on said fixed member for supporting said wedge member, said attaching means including portions spaced outwardly from the face of said fixed member and extending laterally in opposite directions, said portions being appreciably wider in a horizontal direction than in a vertical direction, and said wedge member having a portion adjacent the top end thereof provided with a vertically elongated slot shaped to pass over said attaching means when said wedge is turned to a substantially horizontal position and to be retained positively thereby when in vertical position when the wedge is vertical.

4. A window sash lock comprising, in combination, a fixed member adapted to be attached to an upper window sash, a wedge shaped member adapted to depend from said fixed member and to receive a vertical force from the lower window sash, and attaching means on said fixed member for supporting said wedge member, said attaching means including a pair of laterally spaced oppositely extending ears projecting outwardly from the face of said fixed member and extended parallel to the window pane, said ears having an overall width in a horizontal direction appreciably greater than their vertical width, and said wedge member having a portion adjacent the top end thereof which is thinner than the outward projection of said ears and which is provided with a vertically elongated slot shaped to pass over said ears when said wedge is turned to a substantially horizontal position and to pass between said ears and said fixed member to be retained thereby when the wedge is vertical.

5. A window sash lock comprising, in combination, a fixed member adapted to be attached to an upper window sash, a wedge shaped member adapted to depend from said fixed member and to receive an upward force from the lower window sash, and attaching means on said fixed member for supporting said wedge member, said attaching means including a nail having a transversely elongated head spaced outwardly from the face of said fixed member, and said wedge member having a portion adjacent the top end thereof which is thinner than the distance spacing said head from said fixed member and provided with a vertically elongated slot which is adapted to pass over said nail head when the wedge member is turned to a horizontal position and to be retained against all horizontal displacement at said portion by said nail head when the wedge member is hanging in its normal vertical position.
